UNITED STATES PATENT OFFICE.

AMOS WHITTEMORE, OF CAMBRIDGEPORT, MASSACHUSETTS.

IMPROVEMENT IN CAR-STARTERS.

Specification forming part of Letters Patent No. 177,604, dated May 16, 1876; application filed November 20, 1875.

To all whom it may concern:

Be it known that I, AMOS WHITTEMORE, of Cambridgeport, in the county of Middlesex and State of Massachusetts, have invented a new and valuable Improvement in Car-Starters; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan view of my mechanism for starting cars, and Fig. 2 is a longitudinal vertical sectional view of the same. Fig. 3 is a side view thereof, and Figs. 4 and 5 are detail views.

This invention has relation to improvements in car-starters, wherein the momentum of the car is employed for storing up a reserve force, which, when expended, will start the car after a stoppage.

The nature of the invention consists in a gear-wheel eccentrically keyed upon a shaft arranged above the axle of a car, which, when thrown into gear with a gear-wheel upon the axle during the progress of the car, will raise the forward end thereof, so that when the brakes are applied, at the moment the car reaches the necessary elevation, a reserve force will be accumulated, which, when expended after a halt, will start the car, independent of any power exercised by the draft-animals, thereby relieving them of great strain and labor. It also consists in combining with the operating eccentric gear-wheel an eccentric wheel keyed upon the shaft of the former at each side of the car, which wheels will bear upon the axle of the car when its end is raised by the eccentric gear-wheel, thereby preventing it from tilting or swaying from side to side. It also consists in combining with the supporting-eccentrics and the lifting-eccentric a lever or levers, whereby the said raising-eccentric is thrown into gear with the axle, and thereby causes the momentum of the car to raise its end, whereby a reserve force is stored up for starting the car. It also consists in means, substantially as hereinafter explained, whereby, at the starting of the car, this reserve force may be expended and the car moved forward without effort on the part of

the draft-animals, as will be fully understood from the following description.

In the annexed drawings, A designates the body of a street railway car, which is mounted on wheels B, applied on axles B', the axle-boxes *a* of which are allowed free vertical play in the brackets C by being guided in vertical slots *b* formed therein. This play I take advantage of for keeping the wheels on the track while using the starting device, as will be hereinafter explained. C' represents a second shaft, rotating in bearings in hangers *c*, and arranged directly over shaft B', upon which shaft C is eccentrically keyed a gear-wheel, D, and at each side thereof an eccentric wheel, E.

Gear-wheel D and eccentrics E are each provided with a peripheral notch, *d*, which overhangs shaft B', so that under ordinary circumstances the said wheel will not be in contact therewith. As shown in Fig. 1, shaft B' is provided with a gear-wheel, *e*, keyed thereon or cast therewith, with which the eccentric gear-wheel D will engage under circumstances hereinafter explained. Eccentrics E are provided with pins *f* projecting therefrom, with which vertically-vibrating angular levers F F' are adapted to engage. Lever F has its fulcrum at *g* in a hanger, *g'*, on the front end of the car, and it extends upward within convenient reach of the driver, its rear end being under pin *f*. When lever F is thrust to the front it will, through the medium of pin *f* and eccentric E, bring the eccentric gear-wheel D into engagement with gear-wheel *e*, when the rotation of the axle will cause the eccentric wheel to turn, and thereby raise the front end of the car, as shown in Fig. 5, when a cam, G, on shaft C', will be brought forcibly into contact with a vertically-vibrating rod or bar, H, pivoted to the under side of the car, and pivotally connected, by means of jointed locking-rods *h h'*, the latter being pivoted to bar H at *i*, to one end of a horizontally-vibrating bar, I, pivoted to the lower end of a hanger, *j*, rigidly secured to the car-bottom. Bar I is connected, by means of rods *k k'*, to brake-rods *l* of brake-shoes *l'*; consequently, when bar H is vibrated by the force applied by cam G, it will actuate bar I and operate the brakes automatically, thus arresting the car and holding it in the raised position shown in Fig. 5.

Locking-rods h h' will be caused to flex upward, thereby releasing the brakes by means of a trigger, m , attached to a vertically-vibrating lever, J , having two power-arms, n n' , the one extending upward and the other downward, as shown in Fig. 2. Trigger m is operated from either end of the car, to "let go brakes," by means of connecting-rods c d ', which extend front and rear from lever J , and are rigidly secured to one end of a vertically-vibrating angular lever, K , having its fulcrum at o in an arm, a' , extending downward from the bottom of the car. Levers K are operated by means of the ordinary brake-rods L , having a worm, p , working in a screw-threaded sleeve, q , rigidly secured in the front and rear ends of the car, with which the said levers are connected in any suitable manner, but preferably by means of a disk, r , rigidly secured to the said rod, and confining the bifurcated end of the said levers thereto. When rods L are caused to rotate by any suitable manner, so as to raise the power-arms of levers K , the trigger m will unlock rods h h' , and thus take off brakes. If the slightest start be now given to the car its weight and that of its contents will actuate eccentric D , causing it to rotate the car-axle B' through the medium of gear-wheel e thereon, thereby turning the wheels and starting the car, thus doing away with the immense strain put upon the draft-animals when overcoming the inertia of the car.

Lever F' , before alluded to, is of angular form, and has its fulcrum in a hanger, t , depending from and rigidly secured to the car-bottom, its weight end being in engagement with pin f on the other eccentric wheel E , and its power end connected by means of a rod, u , to a vertically-vibrating lever, M , on the rear end of the car. When this lever is thrust outward it will bring eccentric gear-wheel D into engagement with gear-wheel e on axle B' , thus raising the rear end of the car, and enabling me to give the said car an independent start in whichever direction it may be going.

In practice, operating-levers M and F' will be returned, after being actuated, to their normal positions by means of a spring, S , one end of which is secured to the car-bottom, and the other connected by means of a rod, u' , to the upper end of angular lever F' , thus placing or setting them ready for a subsequent actuation. Lever F , on the front end of the car, will also be returned to its position by means of a similar spring, S' , which is secured to the car-bottom and connected to the power-arm of the said lever, as shown in Fig. 1.

In practice, eccentric wheels E will be suffi-

ciently large, not only to prevent the car from tilting, but also to prevent the eccentric gear-wheel D from binding when in engagement with gear-wheel e on the shaft, the effect of which is that the starter is rendered far more sensitive, and all unnecessary wear of the said gear-wheels is prevented.

In practice, brake-rods L will be utilized, independently of any other function heretofore explained, for operating the brakes, by connecting the latter with the said rods by means of rods, ropes, or chains v .

It will be readily understood from the above explanation that the power exercised by eccentric gear-wheel D will increase with the weight of the passengers in the car—in other words, will be proportionate to the inertia to be overcome. Trigger m , above explained, will also be retracted from jointed rods h h' by means of a similar spring, S^2 , one end of which is secured to the car-bottom, and the other connected by a rod, x , to the lever J , thus leaving them free to gravitate to a locking position, as above set forth.

The starting devices above described may be covered in or not, as I may elect, to protect them from accumulations of snow, ice, and other clogging substances.

What I claim as new, and desire to secure by Letters Patent, is—

1. In combination with the vertically-movable axle B' , having gear-wheel e , the eccentric gear-wheel D , adapted to be thrown into engagement with gear-wheel e , substantially as specified.

2. In combination with the eccentric gear-wheel D and the vertically-movable axle B' , having gear-wheel e , the supporting-eccentrics E , substantially as specified.

3. In combination with shaft C' , having eccentric gear-wheel D and eccentric wheels E , and the shaft B' , having gear e , the operating-levers F F' , engaging with the said eccentric wheels, substantially as specified, and for the purpose set forth.

4. In combination with the shaft C' , having cam G , the vertically-vibrating lever H , jointed locking-rods h h' , lever I , rods k k' , and the brakes l l' , substantially as specified.

5. In combination with the upwardly-flexing joint-rods h h' , the trigger m , operated substantially as set forth.

In testimony that I claim the above I have hereunto subscribed my name in the presence of two witnesses.

AMOS WHITTEMORE.
